REFRIGERATION

Henry B. Pownall, York, Pa., assignor to York
Corporation, a corporation of Delaware

Application February 26, 1943, Serial No. 477,243

8 Claims. (Cl. 62—115)

This invention relates to refrigeration and particularly to refrigerative circuits in which the evaporator is fed by means of an expansion valve of the superheat controlled type. Such valves are too familiar to require detailed description but characteristically the control is exerted in part by a thermal bulb subject to the temperature of vaporous refrigerant leaving the evaporator. They operate to control the rate of supply of refrigerant to the evaporator in such a way that the vapor leaving the evaporator is always superheated.

Normally there are only two sources of heat for superheating this vapor. The first source is the medium cooled by the evaporator. The second source is the liquid refrigerant entering the evaporator. When such a control is applied to a low temperature system, the available heat is insufficient to give a degree of superheat great enough to assure precise control of the valve.

The present invention in its broadest aspects contemplates the supply of heat to vaporous refrigerant leaving the evaporator and before the refrigerant affects the thermal bulb, such heat being supplied at a substantially uniform rate and being heat additional to that which may be derived from either of the two sources above named.

While the widest latitude is possible in the selection of the source of heat, it is desirable to use waste heat from the refrigerative circuit. This can be done in various ways. While the invention can be applied to simple circuits, it is chiefly valuable in low temperature refrigeration. Most low temperature circuits are either of the cascade type or of the compound type. Since the invention can be applied very effectively to circuits of these two types, it will be described as so embodied, without, however, implying any necessary limitation to either of these two arrangements.

In the drawing which is largely diagrammatic, Fig. 1 shows a compound system.

Fig. 2 is a similar view showing a cascade system.

In Fig. 1 the low stage compressor appears at 6. Its discharge is connected through the interstage connection 7 with the intake of the high stage compressor 8. Compressor 8 discharges through the hot gas line 9 into the condenser 11 from which liquid refrigerant flows by gravity to the receiver 12. From the receiver 12 the liquid line 13 leads through the zig-zag tube 14 of the expansion cooler whose shell is indicated at 15. Liquid refrigerant cooled by passage

through the coil 14 flows through the expansion valve 16 and connection 17 to the evaporator 18 which is here assumed to be a low temperature evaporator. From the evaporator 18 a suction connection 19 leads through the tubes 21 in the shell 22 of the superheater.

Refrigerant vapor superheated by passage through the tubes 21 flows through the suction line 23 to the intake of the low stage compressor 6. A branch 24 leads from the liquid line 13 to the space within shell 22 around the tubes 21. From this space a line 25 leads to the expansion valve 26 which controls the flow of refrigerant to the space within the expansion cooler 15 around the tube 14. From the shell of the expansion cooler 15 a line 27 leads to the interstage connection 7. Expansion valve 16 has a regulatory thermal bulb 28 which is mounted on the suction connection 23 and is connected with expansion valve 16 by the capillary 29. Thus the bulb is subject to the temperature of the refrigerant flowing to the low stage compressor 6 after being superheated by passage through the tubes 21.

Expansion valve 26 has a regulatory thermal bulb 31 which is shown so located as to be subject to temperature in the interstage connection 7 beyond its junction with the line 27. The bulb 31 is connected with the valve 26 by the capillary 32. It will be observed that the direct expansion cooler in shell 15 is in effect a subordinate evaporator in which the suction pressure is interstage pressure and consequently a pressure higher than that which exists in the evaporator 18. Thus the expansion cooler operates at a temperature and pressure higher than those characteristic of the main evaporator 18 and it functions to cool liquid refrigerant flowing to the main evaporator.

In Fig. 1 there are, in a sense, two circuits and these circuits are distinct to the extent that there are two evaporators each with distinct connections. The important thing is that liquid refrigerant flowing to the direct expansion cooler 15 exchanges heat with the cold vaporous refrigerant drawn from the main evaporator 18 and thus superheats that vapor before it reacts upon the thermal bulb 28. This improves the regulatory performance of the expansion valve 16 and at the same time penalizes the system to the least degree practicable. It must be remembered that accurate control of the valve 16 is so important that it may be sought even at the sacrifice of some theoretical efficiency.

The cascade system shown in Fig. 2 is quite similar in its ultimate function. In the cascade

system there are two refrigerative circuits, one operating in a relatively high and the other in a relatively low temperature range. These circuits are normally interconnected to the extent that the evaporator of the high temperature circuit and the condenser of the low temperature circuit are combined in one surface heat exchanger.

According to the present invention, the two circuits are further related by the interposition of the superheater in which warm liquid refrigerant flowing from the condenser of the high temperature circuit exchanges heat with the cold vaporous refrigerant flowing from the evaporator of the low temperature circuit.

In Fig. 2 the compressor of the high temperature circuit is indicated at 41 and discharges through a hot gas line 42 to a condenser 43 from which the liquid line 44 leads through the shell 45 of the superheater, the flow being around the tubes 46 within the shell and thence to connection 47 which leads to the expansion valve 48. The expansion valve 48 controls delivery of liquid refrigerant to the space within the tubes 49 within the shell 51 of the heat exchanger. From the tubes 49 evaporated refrigerant flows through the suction line 52 to the intake of compressor 41. The expansion valve 48 is of the superheat controlled type and includes a thermal bulb 53 which is connected with the valve by capillary 54 so as to participate in the control of the valve 48. The compressor of the low temperature circuit is indicated at 55. It discharges through the hot gas line 56 into the space within the shell 51 around the tubes 49. Compressed refrigerant is condensed in this shell and flows by way of line 57 to the main expansion valve 58. From the expansion valve 58 refrigerant flows to the main evaporator 59. From the evaporator 59 a suction line 61 leads to the entrance end of the tubes 46 within the superheater shell 45. From the discharge end of the tube 46 the superheated refrigerant flows by line 62 from the intake to compressor 55. Expansion valve 58 is of the superheat controlled type and includes a thermal bulb 63 subject to the temperature of vaporous refrigerant flowing through the line 62. The bulb 63 is connected with the valve 58 by the usual capillary 64.

Here again superheat is added to vapor leaving the main evaporator and is heat additional to that derived from the medium cooled by the evaporator 59 and additional to any heat which might be derived from liquid refrigerant fed to the evaporator 59.

In the embodiment of Fig. 2, the refrigerative circuits are distinct except that they exchange heat at two points. The action is similar to that characteristic of Fig. 1 in the fact that the liquid which flows through the superheater is evaporated to cool liquid which thereafter is fed to the main evaporator.

While the invention has been described as applied to two typical circuits using more than one compressor, this is intended to illustrate the best known ways of applying the invention to those circuits which are commonly used for low temperature refrigeration.

The invention is not limited to use in either of the systems illustrated, for in its broadest aspects it involves a supply of superheat to vapor leaving the main evaporator, the heat so supplied being additional to heat derived from the medium cooled by the evaporator and from liquid refrigerant flowing to the evaporator. Obviously

this broad idea can be applied to a simple circuit in various ways.

What is claimed is:

1. The combination of a refrigerative circuit including an evaporator to which refrigerant is delivered in the liquid phase and from which refrigerant is withdrawn in the vapor phase; and means for delivering at a substantially uniform rate to the off-flowing vapor to superheat the latter, heat additional to that derived from the medium cooled by the evaporator and from a source external to the circuit through the evaporator.

15 2. The combination of a refrigerative circuit including an evaporator to which refrigerant is delivered in the liquid phase and from which refrigerant is withdrawn in the vapor phase; an expansion valve of the superheat control type regulating the delivery of liquid refrigerant to the evaporator and including a heat sensitive 20 controlling element subject to the temperature of off-flowing vaporous refrigerant beyond the evaporator; and means for delivering at a substantially uniform rate to the off-flowing vapor, before the vapor reacts upon said sensitive element, heat additional to that derived from the medium cooled by the evaporator and from a source external to the circuit through the evaporator.

30 3. A refrigerative system of the compressor, condenser, evaporator circuit type having refrigerant paths which are distinct at least to the extent that there are two evaporators and distinct connections for delivering liquid refrigerant to, and for withdrawing vaporous refrigerant from, respective evaporators; and heat exchanging means for delivering heat from liquid refrigerant flowing to one of said evaporators to the cold vaporous refrigerant flowing from the other of said evaporators.

40 4. A refrigerative system of the compressor, condenser, evaporator circuit type having refrigerant paths which are distinct, at least to the extent that there are two evaporators each with 45 its own connections for supplying liquid refrigerant and withdrawing vaporous refrigerant, one of said evaporators being the main evaporator which carries the refrigerative load and operates at a low temperature, and the other evaporator operating at a higher temperature and serving to abstract heat from liquid refrigerant to be supplied to the main evaporator; and heat exchanging means serving to deliver heat from liquid refrigerant flowing to said other evaporator, to 55 cold vaporous refrigerant flowing from the main evaporator.

5. The combination of two refrigerative circuits each of the compressor, condenser, evaporator circuit type, the second operating in a lower temperature range than the first, said circuits exchanging heat through two surface interchangers, one of which interchangers serves as the evaporator of the first circuit and the condenser of the second circuit, and the second of 60 which interchangers transfers heat from the warm liquid refrigerant of the first circuit to cold vapor leaving the evaporator of the second.

6. The combination of two refrigerative circuits each of the compressor, condenser, evaporator circuit type, the second operating in a lower temperature range than the first, said circuits exchanging heat through two surface interchangers, one of which interchangers serves as the evaporator of the first circuit and the condenser of the second circuit, and the second 70

of which exchangers transfers heat from the warm liquid refrigerant of the first circuit to cold vapor leaving the evaporator of the second; an expansion valve in the second circuit controlling delivery of liquid refrigerant to the evaporator; and thermostatic means subject to temperature of refrigerant in the second circuit beyond the second heat exchanger, and exercising a controlling effect on the expansion valve.

7. A refrigerative circuit comprising compressors connected in stages; a condenser to which the high stage compressor delivers; an evaporator fed from the condenser; a suction connection from the evaporator to the intake of the low stage compressor; a surface cooler interposed in the flow path from the condenser to the evaporator and having expansion cooling means connected with an interstage compressor connection and with a branch liquid supply connection from the condenser; and a surface heat exchanger interposed in said branch connection and in the suction connection between the evaporator and low stage compressor.

8. A refrigerative circuit comprising compressors connected in stages; a condenser to which the high stage compressor delivers; an evaporator fed from the condenser; a suction connection from the evaporator to the intake of the low stage compressor; a surface cooler interposed in the flow path from the condenser to the evaporator and having expansion cooling means connected with an interstage compressor connection and with a branch liquid supply connection from the condenser; a surface heat exchanger interposed in said branch connection and in the suction connection between the evaporator and low stage compressor; and an expansion valve of the superheat control type interposed between the surface cooler and the evaporator and including a thermal element for controlling the valve, subject to the temperature of refrigerant in the suction connection between the heat exchanger and the low stage compressor.
